DE-ICING APPARATUS FOR AIRPLANES

William C. Clay, Buckroe Beach, Va.

Application March 10, 1939, Serial No. 261,089

14 Claims. (Cl. 244—134)

This invention relates to airplanes and more particularly to means for preventing the formation of ice on the spinner or other surface of an airplane exposed to ice forming conditions in an airstream.

It is well known that ice formation on the spinners of propellers interferes in a marked degree with the operation of the propeller, particularly propellers of the variable pitch blade type, owing to the fact that, when flying under ice forming conditions, liquid particles in the airstream not only congeal on the spinner but also tend to collect and solidify around the roots of the propeller blades and prevent proper functioning of the pitch changing mechanism. Furthermore, the accretion of ice on the spinner and nose of the fuselage materially increases head resistance and consequently retards the speed of the airplane.

The object of the invention is to overcome these objectionable features by providing a rotating shield or disk disposed in advance of the spinner or nose of the fuselage and which will intercept any and all of the liquid particles in the airstream that normally would fall or impinge on the surface of the spinner, nose or other exposed surface of an airplane.

A further object of the invention is to provide a flexible shield or disk mounted to revolve with the spinner and susceptible of radial stretch or distention under the influence of centrifugal force to automatically loosen and dislodge any particles of liquid, ice or snow in the airstream which may be deposited thereon when the airplane is in flight.

A further object is to provide a de-icing shield or disk comprising a plurality of flat flexible members formed of rubber or other elastic material and each provided with a series of radiating slits or incisions defining independent stretchable segments, said members being so constructed and arranged that the slotted portion of one member overlaps the solid portion or hub of an adjacent member whereby to present a de-icing surface, the effective area of which approximates the diameter of the shield.

A still further object of the invention is to provide a de-icing shield of simple and inexpensive construction capable of being quickly attached to the spinner or other exposed surface of an airplane without necessitating any material structural change therein and which may be rotated either by the spinner or by an auxiliary motor or other source of power on the airplane.

55 In the accompanying drawing forming a part

of this specification and in which similar numerals of reference indicate corresponding parts in all the figures of the drawing:

Figure 1 is a perspective view of an airplane propeller of the variable pitch blade type showing the de-icing shield or disk in position on the spinner thereof,

Figure 2 is an enlarged transverse sectional view taken on the line 2—2 of Figure 1,

Figure 3 is a detail vertical sectional view illustrating a de-icing shield of the single disk type, and

Figure 4 is a side elevation, partly in section, showing the de-icing shield mounted on the nose of an airplane.

The improved de-icing shield or disk forming the subject-matter of the present invention may be used in connection with any surface of an airplane exposed to ice forming conditions in an airstream, and in Figure 1 is shown applied to a standard propeller of the feathering or variable pitch blade type, in which 6 designates the propeller hub, 6 the blades and 7 the spinner secured to and mounted for rotation with the hub in the usual manner.

The device comprises a flat flexible inner member or disk 8 preferably of a diameter equal to or slightly larger than the diameter of the spinner 7 so as effectually to intercept any and all liquid particles in the airstream that normally would fall or impinge on the exposed surface of said spinner. The shield or disk 8 is circular in contour and preferably formed of rubber or other suitable material possessing sufficient inherent elasticity to cause distention or stretching of said material by centrifugal force when liquid particles are deposited thereon during rotation of the disk.

The material of which the disk is formed is relatively thick at its point of attachment to the spinner to form a plano-convex hub portion 9 and then gradually decreases in thickness from the hub to the outer periphery of the disk to form a flexible skirt having spaced radiating slits or incisions 10 therein and defining independent stretchable portions or segments 11. The slits or incisions 10 extend entirely through the disk and sever the skirt along radial lines from the hub to the periphery of said disk so that the segments 11 are free to stretch independently of each other, thereby to loosen and dislodge any snow or liquid particles that may be deposited thereon.

Associated with the inner disk 8 is a smaller outer disk 12 similar in construction to the in-

ner disk and so positioned with respect thereto that the flexible segments 13 of the outer disk will overlap the hub portion 8 of the inner disk and thus present a substantially unbroken de-icing surface in advance of the spinner for intercepting liquid particles in the airstream and consequently prevent snow and ice from finding lodgment on the spinner or around the roots of the propeller blades 6 and interfering with the 10 pitch changing mechanism thereof.

Extending laterally from the free end of the spinner 7 and preferably formed integral therewith is a bolt or stud 14 and the hubs of the inner and outer disks are provided with registering openings 15 adapted to receive said stud. Interposed between the flat face of the inner disk 8 and the spinner 7 is a spacing washer 16 and threaded on the outer end of the bolt 14 is a clamping nut 17 which engages a washer 18 and 20 serves to clamp the disks firmly in position on the spinner so as to rotate therewith. The inner face of the spacing washer 16 is preferably curved at 19 to conform to the outer surface of the nose of the spinner 7, as best shown in Figure 4 25 of the drawing.

It will be noted that the inner and outer disks are assembled on the supporting stud 14 with the convex faces of the hubs thereof disposed in contact with each other so as to properly separate 30 the outer edges of the disks and render the employment of an intermediate spacing washer unnecessary.

In operation, when an airplane is flying under ice forming conditions, the rotating shield, 35 owing to its size and position on the spinner, will intercept any liquid particles in the airstream tending to collect on said spinner. Should ice form on the flexible segments of the shield, the additional weight of the ice accretions thereon augmented by centrifugal force incident to 40 rotation of the shield, will distend or stretch said segments radially so as to cause the ice to loosen and separate from the segments and be thrown off harmlessly without allowing any deposit of 45 ice on the spinner or around the roots of the propeller blades so that head resistance is reduced to a minimum and proper functioning of the pitch changing mechanism assured.

In Figure 3 of the drawing, there is illustrated 50 a modified form of the invention, in which but a single shield or disk 20 is used, said shield or disk being supported on the nose of the spinner by a removable stud or bolt 21, the head of which is provided with anchoring spurs 22 adapted 55 to bite into the inner surface of the spinner to prevent rotation of said bolt. It will be understood, however, that the de-icing shield may be formed of any desired number of flexible disks and that the supporting studs for the disks may 60 be formed integral with the spinner or separate therefrom as desired.

The de-icing shield is also applicable to the fuselage of an airplane to prevent ice formation on the nose thereof, and in Figure 4 of the drawing, I have shown an embodiment of the invention capable of performing that function. When the device is used for this purpose, I provide a suitable motor 23 preferably mounted in the nose of the fuselage and having its power shaft 70 24 journaled in suitable bearings 25 with its outer end extending through the nose 26 of the fuselage to form a support for a radially slotted flexible shield or disk 27, said disk being clamped to the shaft 24 by a nut 28 so as to rotate 75 with the shaft. If an electric motor is employed,

the terminals 29 of the electric conductors may extend to a suitable switch located in the cabin of the fuselage so that, when the plane is traveling under ice forming conditions by merely closing the switch, the shield will be caused to 5 rotate in advance of the fuselage and intercept any liquid particles in the airstream which otherwise would fall on the nose and form ice thereon. When the shield shown in Figure 4 is not in use, the switch is actuated to cut off current 10 to the motor, and inasmuch as the shield 27 is formed of flexible material, the pressure of air on the shield will flatten said shield against the nose of the fuselage, as indicated by dotted lines at 30, so that the shield will not offer any drag 15 or head resistance during the flight of the airplane. As the lodgment or formation of ice or snow around the roots of the propeller blades materially interferes with the pitch changing mechanism thereof and sometimes causes said 20 pitch changing mechanism to cease functioning entirely, the provision of a shield to avoid these objectionable features is very desirable as a safety factor when flying under ice forming conditions.

While I have shown and described the shield in 25 connection with the spinner and nose of an airplane, it will, of course, be understood that said de-icing shield may be used in connection with any surface of an airplane exposed to ice forming conditions in an airstream. It will also be 30 understood that the diameter of the shield may be varied at will without departing from the spirit of the invention.

Having thus described the invention, what is 35 claimed as new is:

1. In an airplane, the combination with a member having a surface exposed to ice forming conditions, of a substantially flat radially expansible shield mounted for rotation on said member.

2. In an airplane, the combination with a member having a surface exposed to ice forming conditions, of a substantially flat elastic disk mounted for rotation in advance of said member and provided with independent segments movable to 40 distended position when ice forms thereon to 45 loosen and separate the ice therefrom.

3. In an airplane, the combination with a member having a surface exposed to ice forming conditions, of a substantially flat elastic shield mounted for rotation on said member in advance 50 thereof and provided with radial incisions defining independent segments adapted to be stretched radially by centrifugal force to dislodge ice 55 deposits thereon.

4. In an airplane, the combination with a member having a surface exposed to ice forming conditions, of an elastic disk mounted for rotation in advance of said member and provided with normally closed radial slits intersecting the 60 periphery of the disk.

5. In an airplane, the combination with a member having a surface exposed to ice forming conditions, of a substantially flat radially expansible shield mounted for rotation in advance of said member and provided with peripheral portions 65 independently distensible radially under the influence of centrifugal force and the weight of ice deposited thereon for loosening and separating the ice from said portions.

6. In an airplane, the combination with a member having a surface exposed to ice forming conditions, of a radially expansible shield mounted for rotation in advance of said member and comprising a plurality of substantially flat elastic disks of different sizes each having radially slit 75

peripheral portions, the slit portions of one disk overlapping the slit portions of an adjacent disk.

7. In an airplane, the combination with a member having a surface exposed to ice forming conditions, a supporting stud carried by said member, and a plurality of elastic disks mounted on the stud and provided with radial slits defining independently distensible sections.

8. In an airplane propeller, the combination with a spinner, of a support carried by the spinner, and a substantially flat radially expansible shield independent of the spinner mounted on the support in advance of said spinner to turn therewith for preventing formation of ice on said spinner.

9. In an airplane, the combination with a propeller and spinner, of a support projecting from the end of the spinner, and a flexible shield independent of the spinner mounted on the support to turn with said spinner, said shield being of a diameter greater than the maximum diameter of the spinner thereby to intercept liquid particles in an airstream and prevent the formation of ice on the spinner and around the roots of the propeller blades.

10. A de-icing attachment for airplanes comprising a radially expansible elastic member having incisions extending inwardly from the peripheral edge thereof and defining separate portions adapted to be stretched by centrifugal force when ice forms thereon, and means for supporting said member for rotation on the exposed surface of an airplane.

11. A de-icing attachment for airplanes comprising a plurality of rotating elastic members of different sizes disposed one in advance of the other and each provided with normally closed radial slits extending inwardly from the periph-

ery thereof to form a flexible skirt, said skirt being adapted to be stretched by centrifugal force when ice forms thereon to separate the ice therefrom, and means for supporting said members for rotation in advance of a member having a surface exposed to ice forming conditions in an airstream.

12. In an airplane, the combination with a spinner having a stud extending laterally therefrom, a plurality of flexible disks mounted on the stud to turn with the spinner, each disk being provided with a solid hub portion and a flexible skirt having radiating incisions formed therein and defining distensible segments, a washer interposed between one of the disks and the adjacent face of the spinner, and a nut engaging threads on the stud and bearing against the other disk.

13. In an airplane, the combination with a spinner, a supporting stud mounted on the spinner, a plurality of flexible disks of different sizes fitted on the stud and each having a solid piano-convex hub portion and a flexible skirt integral therewith, each skirt being formed with radiating incisions defining independent distensible segments, said disks being disposed one in advance of the other with the distensible sections on one disk overlapping the junction of the hub portion and distensible segments of an adjacent disk.

14. In an airplane, the combination with a propeller and spinner, of a substantially flat radially slotted elastic disk independent of the spinner disposed in advance of said spinner and mounted to turn therewith, said disk being of sufficient size to intercept liquid particles in an airstream and thereby prevent the formation of ice on the spinner and around the roots of the propeller blades.
